Primary Examiner — Bridget L Eland*Assistant Examiner* — Lauren McVey*(74) Attorney, Agent, or Firm* — Vedder Price P.C.(57) **CLAIM**

The ornamental design for a breastfeeding top, as shown and described.

DESCRIPTION

FIG. 1 is a front perspective view of a breastfeeding top of the present invention shown in an environment;

FIG. 2 is an alternate front perspective view of the breastfeeding top shown in an alternate environment;

FIG. 3 is another alternate front perspective view of the breastfeeding top shown in another alternate environment;

FIG. 4 is a side perspective view of the breastfeeding top shown in the alternate environment state;

FIG. 5 is an alternate side perspective view of the breastfeeding top shown in an environment; and,

FIG. 6 is a back perspective view of the breastfeeding top shown in the alternate environment state.

The broken lines shown in the views are directed to environment and form no part of the claimed design.
